UNITED STATES PATENT OFFICE

WILLIAM T. RAY, OF WICHITA, KANSAS

LOCOMOTIVE DRAFT APPLIANCE

Application filed March 26, 1929. Serial No. 350,105.

The present invention relates to locomotive draft appliances of the character more directly associated with the smoke stacks and nozzles for the directing of live steam or the exhaust steam from the cylinders thru the smoke stacks to augment furnace draft.

Because of the unusual conditions under which a locomotive furnace must be designed and operated, it is necessary that a forced draft be provided, since the natural draft under such adverse conditions is very poor. A blower, such as a discharge of live steam is used in the stack to create a draft thru the furnace when the locomotive is not moving and when the locomotive is in operation the exhaust from the cylinders is discharged under the stack to create the furnace draft. After the steam has expanded in the cylinders of the locomotive it is carried thru an exhaust nozzle and directed thru an exhaust nozzle tip which is located directly under the center of the stack. The steam in passing upwardly thru the stack to the atmosphere mixes with the furnace gas and pulls it out causing a partial vacuum in the smoke box. Thus the gas from the furnace is induced to flow from the furnace thru the flues, down under a baffle wall, then thru a suitable screen, and finally mixed with the exhaust steam to be carried out thru the stack to the atmosphere.

At present there is considerable loss in the efficiency of this equipment caused by the steam from the exhaust tip blowing up thru the center of the stack and not completely filling it, thus allowing a down movement of air around the inside of the stack to replace the gas pulled out by the exhaust, which checks the draft of the furnace to a certain extent, by reducing the vacuum that could be obtained if the stack were completely filled with gas and exhaust steam moving out to the atmosphere. An attempt has been made to overcome this by using devices or formations directly associated with the nozzle tip for the purpose of breaking up the exhaust and causing it to fill more of the area of the stack. This equipment has been partially successful to this end, but this gain

is more than offset by the loss in added resistance to the exhaust which causes a higher back pressure with a resulting loss of power.

The principal objects of the present invention are to provide appliances which make for efficiency and economy, by utilizing the major portion, if not all of the steam directed upwardly from the nozzle to cause an efficient furnace draft and to reduce the back pressure or resistance to movement of the exhaust steam from the cylinders by appliances which permit the use of nozzles having larger openings than those in common use; and to provide appliances which may be attached to or used with equipment common to locomotives in use at the present time.

Other objects and advantages of the invention will appear in the following detailed description, taken in connection with the accompanying drawing, forming a part of this specification, and in which drawing:

Figure 1 is a fragmentary side elevation of a locomotive, parts being broken away and shown in section to disclose details, the locomotive being equipped with a draft appliance according to the present invention.

Figure 2 is a side elevation of a draft appliance or exhaust deflector constructed according to the present invention.

Figure 3 is a bottom plan view of the same.

Figure 4 is a central vertical sectional view.

In the drawings where like characters designate like or similar parts thruout the views, A designates a locomotive boiler including flues or fire tubes B; C the smoke box and its associated smoke stack D; E an engine cylinder; F the associated steam chest or valve chamber; G the exhaust nozzle with suitable tip H axially aligned with the smoke stack D, and J the steam pipe for supply of live steam from the boiler A to the steam chest F; K the baffle wall against which the flue gases impinge and are guided to the smoke box C and finally thru the smoke stack D after passing thru suitable screen L. All of the foregoing may be of any suitable or approved design common to locomotives

now in use with the exception that the orifice of nozzle tip H may be larger than is commonly provided so as to reduce back pressure in the exhaust ways from the locomotive cylinders, loss of efficiency of the exhaust steam as a draft producing medium being avoided by use of the present invention which may be termed an exhaust deflector, designated as M in the drawing.

10 In a practical installation this exhaust deflector may be attached to or supported by a saddle casting N provided beneath the smoke stack D of some locomotives or may be supported in any suitable manner beneath the smoke stack so as to align axially therewith and form an entrance way for the gases to the stack.

15 The main body portion of the exhaust deflector M is preferably a casing or shell, preferably elongated and cylindrical in shape. To strengthen its lower margin, and provide a rounded surface beneath which the gases may flow, this casing or shell may be provided with a rolled over flange 6 extending outwardly from the lower marginal portion of the shell. Suitable lugs 7 are provided, by way of example, having openings 8 to facilitate attachment of the exhaust deflector as will be set forth herein-
20 after. A reduced flange 9 to fit in a suitable seat 10 in the saddle casting N may be provided at the upper marginal portion of the shell altho it is to be understood that any suitable arrangement may be provided
25 to prevent egress or ingress of gases or steam where the exhaust deflector joins the stack D.

30 By use of bolts 11 provided with nuts 12, the exhaust deflector may be secured to the saddle casting N beneath the stack D in such a manner that the way 13 of the exhaust deflector aligns with the way 14 of the stack so that the way 13 acts as an entrance for the
35 gases to the stack.

40 Located within the casing or shell 5 and extending from the internal wall surface thereof are a plurality of wings 15 arranged in inclined relation to the axis of the casing or shell. These wings are preferably flat, that is, providing substantially flat upper
45 and lower surfaces 16 and 17, as shown in Figure 4, which facilitates manufacture, and the lower flat surface 17 serving to guide the exhaust steam issuing from the nozzle tip H to take a spiral path upwardly thru the ways 13 and 14 adjacent the inner wall surfaces of the exhaust deflector and smoke stack. These wings are preferably arranged
50 in the same circumferential zone as shown in Figure 4 and are spaced apart to provide a clear central open way and longitudinally straight clear openings at the interior wall of the shell or casing, when viewed from either end of the shell, as shown in Figure 3.

55 By this arrangement the steam issuing

from the nozzle tip center may pass upwardly thru the smoke stack in substantially the same manner as is common in the present day locomotive, but the steam issuing from the marginal portion of the tip orifice impinges against the under sides of the wings and are caused to move in a spiral path upwardly as indicated by dash lines in ways 13 and 14 of Figure 1, thus completely filling the stack and preventing down movement of air around the inside of the stack as hereinbefore mentioned.

60 By this spacing of the wings, manufacture of the exhaust deflector is greatly facilitated for it may be made of cast metal. The wings 15 may be formed integral with the casing or shell, or they may be welded or otherwise secured, preferably made of case hardened steel or treated as to the lower faces 17 in such a manner that cinders and other foreign matter will have little if any abrasive action thereon.

65 Various minor changes in detail of construction, proportion and arrangement of parts may be resorted to, when required, without sacrificing any of the advantages of the invention as defined in the appended claims.

I claim:

1. An exhaust deflector for locomotives comprising a cylindrical shell, and a plurality of flat wings extending from the internal wall surface of the cylinder and arranged in inclined relation to the axis of the cylinder.

2. An exhaust deflector for locomotives comprising a cylindrical shell, and a plurality of wings extending from the internal wall surface of the cylinder and arranged in inclined relation to the axis of the cylinder.

3. An exhaust deflector for locomotives comprising a cylindrical shell, and a plurality of wings extending from the internal wall surface of the cylinder, said wings arranged in the same circumferential zone and in inclined relation to the axis of the cylinder.

4. An exhaust deflector for locomotives comprising an elongated shell providing a way for the passage of exhaust steam and gases, and a plurality of wings extending from the interior wall surface of the shell and arranged in inclined relation to the axis of the way, said wings spaced apart to provide a clear central open way and longitudinally straight clear openings at the interior wall of the shell, when viewed from either end of the shell.

5. In combination with the smoke stack and exhaust nozzle of a locomotive, a shell disposed below the stack and above the nozzle, and arranged as an entrance way of gases to the stack, and a plurality of inclined wings carried by said shell at the interior thereof.
